UNITED STATES PATENT OFFICE.

STANLEY A. SWEET, OF NEW YORK, N. Y., ASSIGNOR TO SWEET-ORR & CO., INC., OF WAPPINGERS FALLS, NEW YORK, A CORPORATION OF NEW YORK.

COMBINED HAMMER LOOP AND POCKET FOR GARMENTS.

Application filed March 18, 1927. Serial No. 176,430.

This invention is in the nature of an improvement on the pocket of the Carver Patent No. 1,143,038, granted June 15, 1915, which is owned by the owners of the present invention. This patent covers a pocket having a flap which while admitting free access to the pocket, also prevents the accidental escape of the contents of the pocket.

The present invention does the same thing in a modified way, and in addition affords a support for a hammer, as I will proceed now to explain and finally claim.

In the accompanying drawings illustrating the invention, in the several figures of which like parts are similarly designated, Figure 1 is a front elevation and Fig. 2 is a cross-section on line 2—2 of Fig. 1, showing one form of my pocket. Fig. 3 is a front elevation of another form, and Fig. 4 is a front elevation of the pocket shown in Fig. 3, with a hammer shown suspended from the top loop.

The pocket may be arranged upon the hip of an overall or other garment, in the form of a patch, with a loose or full loop crossing one corner of the pocket at its open top or mouth and affording access to the pocket, while preventing accidental escape of its contents, and also serving as a support for a hammer, which last adds to the escape prevention.

In the construction shown in Figs. 1 and 2, the body 1 of the pocket has two parallel sides 2 and 3, of different length, the shorter side being seamed in the side seam A, of the garment B, and the other side and the inclined bottom 4 being stitched to the garment. The top 5 is left open or unattached to form the mouth of the pocket. A loop 6 of greater length than the width of the pocket, has its forward end stitched in the side seam and extends thence to the other side of the pocket across the higher end or top 5 of the pocket and there is secured to the garment over such end by stitches. Thus the forward upper portion of the pocket is left uncovered by the loop to permit the insertion and removal of tools or other articles to be carried in the pocket, while the rear of the loop loosely closes the rear or higher end of the pocket sufficiently to prevent the accidental escape of its contents when the wearer bends or stoops in his work. It is to be noted that the longitudinal edges of the

loop are left free and unattached to the garment excepting at their ends.

The fullness of the loop need not be as great as that indicated in the drawings, but it should be sufficient to permit the convenient suspension of a hammer 7 therein, as indicated in Fig. 4.

As shown in Figs. 1 and 2 the loop 6 has parallel edges, while as shown in Figs. 3 and 4, the loop 8 may have its upper edge straight and its lower edge next to the pocket may be inclined or beveled upwardly from rear to front.

In Figs. 3 and 4 the pocket 1' is shown as made as a parallelogram, with its sides 2' and 3' and end 4' secured to the garment 70 and its upper end 5' left open, as in the form shown in Figs. 1 and 2.

By suspending or supporting the hammer by its head in the loop, with its handle on the outside of the pocket, as shown in Fig. 4, 75 the prevention of accidental escape of the contents of the pocket is enhanced. The hammer will be supported in the loop 6 as in loop 8.

As will be observed, both forms of pockets 80 and loops have an opening 9 between the pocket and loop to facilitate access to the pocket for the insertion and removal of tools and other articles to be carried by the wearer.

In the Carver patent the top of the so-called upper pocket is stitched to the garment and therefore is closed and because it is closed it cannot be used to support a hammer, while it does prevent the escape of the contents of the so-called lower pocket. It 90 is desirable to provide a hammer support, and in order to combine the functions of a pocket for preventing the escape of the tools and the support of a hammer, I have provided the loose gapping loop, over and overlapping the pocket. By omitting the top stitching, the loop serves as a support for a hammer, and with the hammer in the loop, as in Fig. 4, there could be no escape of the tools from the pocket, and without the 100 hammer in the loop, the latter being distended by reason of its overlapping the pocket, serves to prevent the escape of the tools from the pocket.

Variations in construction are permissible 105 within the principle of the invention and the claims following.

What I claim is:—

1. A combined hammer loop and pocket for a garment, having a pocket proper with its upper end open, and a loop secured only by its ends to the garment and extending crosswise of the open end of said pocket and overlying a portion of said open end.
2. A combined hammer loop and pocket for a garment, comprising a pocket proper attached to the garment and having its upper end open, and a loop having free parallel longitudinal edges and overlapping a part of the open end of the pocket and attached to the garment by its ends and with a fullness of the material.
3. A combined hammer loop and pocket for a garment, comprising a pocket proper attached to the garment and having its upper end open, and a loop of greater length than the width of said pocket and having parallel top and bottom edges and overlapping the open end of said pocket, and attached by its ends only to the garment, the loop serving to prevent the accidental escape of the contents of the pocket and also serving as a hammer support.

In testimony whereof I have hereunto set my hand this 16th day of March, A. D. 1927.

STANLEY A. SWEET.
